Assignor to

The Lowell Manufacturing Company

Letters Patent No. 1667-Dated Nov. 11th 1862

The schedule referred to in these Letters Patent and making part of the same
to all whom it may concern

Be it Known that I, Edemir J. Ney, of Lowell, in the County of Middlesex and State of Massachusetts, have originated and designed a new pattern for carpets or other fabrics, of which the following is a full, clear and exact description, reference being had to the accompanying drawings, making part of this Specification.

A. in the centre is a large group of blocks, of various sizes, the spaces between which, are occupied by zig-zag lines, this group is surrounded by the form of scrolls. 1.

The four corners, when matched, form a figure similar to A. in the centre.

Connecting the centre and corner figures are the bands. 2. 3. 4. 5
At the sides and ends of the design are shown, halves of eight pointed figures composed of solid frames, enclosing rosettes, blocks and plain and dotted lines.

The remainder of the design consists of a ground of regular work,

The colors employed for the different portions of the design may, be varied, to suit the taste and wish of the manufacturer.

— Claim —

What I claim as my invention and desire to secure by letters patent, is the design or pattern for carpets, or other fabrics, herein set forth.
